SCREW AND LOCK WASHER ASSEMBLY MACHINE

William Stern, Park Ridge, Ill., assignor to Illinois
Tool Works, Chicago, Ill., a corporation of
Illinois

Application June 5, 1939, Serial No. 277,344

13 Claims. (Cl. 29—84)

The present invention relates to the assembly of related elements and to a method and machine for the production of permanently assembled fasteners and lock washers.

More particularly, the present invention relates to the individual selection of fasteners or fastener blanks from a mass or supply thereof and the individual selection of lock washers from a separate random mass of lock washers followed by the interassociation or assembly of each of the fasteners into operative association with an individual lock washer, and to the discharge of the finished assembly to a thread rolling mechanism or other instrumentality for enlarging the shank of the screw element beneath the washer.

The present invention contemplates the assembly of screw and washer elements by entraining the washer elements upon a conveyor and positively carrying said elements into position adjacent the path of feed of the screw elements, where each screw element is positively moved into the central aperture in a washer.

It is an object of the present invention to provide a method and a machine wherein the washer conveyor remains operative after the association therewith of the fastener element to convey the assembly away from the point of assembly.

The present invention has for its object to provide a construction for assembling washers and screw elements as above, wherein the washers are handled and conveyed by a simplified rotary disk conveyor movable in one direction for continuously moving washers directly from the mass of washers to the assembly point.

It is a further object of the present invention to provide an assembly mechanism as an attachment capable of being readily associated with known or standard thread forming machines or other machines containing mechanisms to which assembled screw and washer units may advantageously be supplied, which attachment comprises a washer supply mechanism, a washer delivery mechanism withdrawing washers from the supply mechanism and conveying the washers to a predetermined point and a mechanism which extracts screw elements from a screw-feeding mechanism and by manipulation of the said screw elements axially shifts each of the elements into a lock washer, the washer delivery mechanism also returning the assembled units to the screw-feeding mechanism for delivery to a thread-forming mechanism.

It is an important object of the present invention to provide means for forcibly telescoping a

fastener into a washer to interengage properly the elements while the respective elements are positively held in alignment.

Another object of the present invention contemplates the provision of an intermittently operated rotary conveyor plate which is provided with peripheral recesses adapted to receive individual washers and is inclined to facilitate movement of the washers into the peripheral recess and to cause excess washers adhering to the face of the conveyor plate to gravitate into the original mass or supply. The step-by-step movement of the conveyor plate also facilitates the movement of the washers into the peripheral recesses of the conveyor plate.

The present invention has for a yet additional object to provide a simplified stop or control mechanism which positively prevents operation of the assembly means when a washer is not delivered to the point of assembly at the proper time for assembly with a screw element. It may occur from time to time that, due to failure to supply the washer hopper or for other cause, the washer-receiving means may not properly receive a washer for conveyance to the point of assembly. It will be obvious from the description which follows that the present invention obviates the possibility of the delivery of unassembled fasteners from the present machine.

Other and further objects and advantages of the present invention will be apparent from the following description when taken in connection with the accompanying drawings, wherein

There is shown in the figures of the present drawings one illustrative machine embodying the principles of the present invention, which machine comprises a screw thread rolling mechanism of a standard known type such as shown in Wilcox Patents Nos. 1,584,263 of May 11, 1926, and 1,798,919 of March 31, 1931. In so far as the essential and standard portions of the thread rolling machine are concerned, namely, the frame and supporting portions, the thread rolling dies, the transfer and starting mechanism, as well as the driving mechanisms for the same, these are in general substantially unmodified. It is accordingly thought unnecessary in disclosing the present invention to reiterate in detail these known constructions.

In accordance with the present invention, the machine disclosed for illustrative purposes comprises a thread rolling machine of the foregoing type provided with one or more additional and substitute mechanisms by which the said machine may be adapted for the production of permanently assembled screw and washer units. These additional and substitute mechanisms comprise, as shown in Figs. 1 to 4, a screw blank hopper and feed mechanism 20, a washer supply and conveying mechanism 22, a screw blank shifting or assembly mechanism 24 for directing each screw blank into association with a washer, and a control system for preventing the actuation of the screw blank assembly mechanism 24 unless a washer is in proper operative position, the last-named control means comprising a washer detector unit 26 and a locking mechanism 28 for the assembly mechanism 24. It should be noted that the washer conveying mechanism 22 and the assembly mechanism 24 comprise driving and control means, both enclosed for convenience within a housing 30 providing a unitary construction which, as will hereinafter more fully appear, may be readily attached as an accessory to standard machines.

The screw thread rolling machine shown in the drawings comprises a main base or pedestal 32 (Figs. 1 and 2) surmounted by an auxiliary base or pedestal 34 secured to or formed integrally with the pedestal 32 and extending upwardly therefrom at an angle of approximately 30 degrees to the horizontal. The frame or pedestal supports among other associated mechanisms a pair of thread rolling dies 36 and 38, the former being fixed with respect to the frame and the latter being relatively movable upon a suitable gate or slide 39. Operation of the slide to produce relative movement of the thread rolling dies is effected from a drive motor 40 (Figs. 2 and 3) through the agency of a drive belt 42, gearing 44, and a crank or pitman 46. A cam 48, rigid with shaft 49 also driven from gearing 44, moves a follower 50 at predetermined times to reciprocate a slide bar starting mechanism which assists and directs the screw blanks into engagement with the dies. The slide bar, designated by the reference numeral 52, is slidably supported in the frame of the machine, as clearly shown in Figure 4, for reciprocation in a direction parallel to the faces of the dies 36 and 38 and as is known carries on its forward end a suitable starter finger (not shown), aligned centrally of the space between the dies. The starter slide bar 52 is moved by the action of the follower mechanism 50 through an arm 56 rigid with a rock shaft 58 journaled in the upper portion of the frame, as shown in Figs. 1, 2 and 4, and which is caused to rock in accordance with the movement of the follower mechanism by a link 60 and arm 62.

The present embodiment provides a guide chute 64 down which the associated screw blank and washer assemblies gravitate to the region of the thread rolling dies and the starter. At the foot of the guide chute 64 is provided a standard transfer mechanism 66 which transfer mechanism engages each assembly at the end of the chute 64 and shifts it laterally through a feed passage into operative position centrally of the space between the thread rolling dies. The guide chute 64 for the assemblies comprises a pair of spaced bars 68 and 70 (Figs. 1, 4, 6, and 8) spaced to engage beneath the head portion of the assemblies, while permitting the screw shank to extend between the intermediate slot or space. A cover rail or bar 72 resides above the space to retain the fastener assemblies within the chute. It will be understood that the bars forming the guide chute 64 are fastened to the frame of the machine by suitable brackets (not shown) and the bars may be preferably relatively adjustable in known manner to accommodate screws or assemblies of varying dimension.

In accordance with the present invention, a quantity of screw blanks is massed in a hopper of the screw blank feeding mechanism 20 and the screw elements are continuously directed one by one along a path of supply in a direction toward the thread rolling mechanism into a point of assembly. The washers are similarly dumped or massed in a feed hopper which is a part of the washer conveying and feeding mechanism 22. At the last-named hopper, the washers are individually received or picked up by a conveyor and moved positively along a predetermined path and out of the mass of washers to the aforementioned point of assembly. At this point and in proper timed relation to the delivery of each washer, the screw element assembly device 24 acts to grasp each screw element and to direct it bodily and axially through the central aperture of an aligned

washer. The washer feed and control mechanism 22, still having positive control of the assembled washers, continues conveying of the assembled units from the point of assembly, and during this movement each assembly is progressively extracted from the influence of the washer feed or conveying means and is directed into the conveying or delivery chute 64 for feeding to the thread rolling dies by way of the transfer mechanism 66. It will be understood that, in accordance with the present preferred embodiment herein described, the surface material forming the shank of the screw blank is caused to flow radially by the action of the thread rolling dies so that the crests of the final threads project outwardly for a sufficient distance to provide an abutment permanently retaining the washer and screw in associated position. Threaded units are discharged from the machine adjacent the lower portion of the fixed thread rolling die 36 into a suitable receiving tray.

The hopper and feed mechanism for the screw blanks

The feed hopper 20, shown in Figures 1 to 3, 25 inclusive, is in general of a type hitherto known and employed upon the thread rolling machines to which reference has previously been made. The construction comprises a hopper casting 14 mounted upon a bracket casting 16 for adjustment at right angles to a guide or delivery chute 78. The guide chute 78 is formed by bars 80 and 82 (Fig. 6) to receive the screw blanks in the same manner as the guide chute 64, and a cover bar 84 (Fig. 1) extends above the other bars. The several bars are mounted at their opposite ends to suitable supporting brackets (not shown) secured to the hopper 14 and are preferably so mounted as to permit adjustment of the bar 80 toward and away from the bar 82, and adjustment of the cover plate 84 toward and away from both of the other plates or bars to accommodate screw blanks of different sizes.

The casting 16, which supports the hopper 14, is adjustably mounted upon the housing 30 which contains the drive and control mechanism for the washer feeding and screw blank assembly means; that is to say, the casting 16 is bolted to a plate 86 as at 88, the bolts passing through vertically elongated apertures to permit relative vertical adjustment of the bracket in the plane of the plate 86 and through the agency of an adjustment screw 90.

It is particularly important to note that the housing 30 is in turn mounted upon the pedestal 32, a slide-way or channel 92 on its opposite surface embracing a plate 94, rigidly bolted to the pedestal 32 as shown in Figure 1. The housing 30, as well as all the elements supported thereby, are accordingly laterally shiftable or adjustable, such adjustment being controllably effected through the agency of a bracket 96 bolted to the end of the plate 94, as at 98, and receiving an adjustment screw 100 threadedly engaging the housing 30 as shown in Fig. 5. Due to the presence of a pair of fixed collars 102 upon the screw shaft 100, rotation of the shaft will shift the housing 30 laterally of the pedestal, in which position it is retained by a jam nut 104.

From the foregoing it will be apparent that the several parts of the present device are relatively adjustable for proper alignment and coordination. It is thought that the importance of these adjustments will become apparent from the following description.

5 Slidably mounted in suitable guide-ways in the hopper casting 14 is a reciprocating plate 106 which, as it moves upwardly, picks up screw blanks from the mass of blanks in the hopper and drops them onto the guide chute 78. A clearing wheel or ratchet 108 normally rotated in a counterclockwise direction as seen in Figure 1 overlies the chute 78 and extends into the hopper to displace any misarranged screw blanks and to assure an uninterrupted procession of blanks or screw elements down the chute 78. It should be noted that the clearing or ratchet wheel 108 is rotatably journaled in a housing 110 pivoted as at 112 upon a bracket 114 projecting forwardly from the lower portion of the hopper casting 14.

10 It will be evident from a consideration of Figures 1 and 3 that the weight of the housing 110 will normally tend to move the assembly in a clockwise direction about pivot 112, such movement being limited by means of an adjustable screw 116 abutting a fixed portion of the hopper. The adjustment device 116 may be readily pre-arranged to space the lower portion of the clearing wheel 108 from the chute bars 80 and 82 a sufficient distance to permit free passage of the head portion of a properly associated screw or screw blank.

15 Ratchet or clearing wheel 108 is driven from the shaft 49 by a pulley 118, driving belt 120, and pulleys 122 which in turn drive a belt 124 to a ratchet wheel drive pulley 126. Vertical reciprocation of the plate 106 is effected by a crank arm or pitman 127 operated from a crank disk 128 journaled on the hopper casting 14 as shown in Fig. 3 and driven by sprocket chain 130 from shaft 132, driven in turn by the gearing 44. The screw blank and feed mechanism is accordingly actuated directly from the drive motor 40 which motivates the operation of the thread rolling device.

20 In operation, the mass or body of screw blanks dumped into the feed hopper 14 is, through the reciprocation of the plate 106, arranged upon the delivery chute 78 along which they gravitate downwardly to the point of assembly.

The hopper feed and conveying mechanism for the washers

25 The washer feed mechanism 22 is shown more in detail in Figures 1, 4, 6, 7, 8, 18, and 19 and comprises an annular shell 134 on the upper surface of the housing 30 and having a wall of increased height at its lower side, providing a hopper for a mass of washers. The annular wall 134 is open adjacent the extremity of the guide chute 78 to permit delivery of the washers directly beneath the end of the guide chute, as will hereinafter more fully appear. The hopper shell 134 embraces and is secured to an annular bracket 136 (Fig. 8) bolted to the top of the housing 30 as at 138. A recessed disc or conveyor plate 140 forms the bottom wall of the hopper (see Figs. 6 and 8). The plate 140, being circular, is mounted for rotation upon the annular shell 136 and secured to a shaft 142 journaled in anti-friction bearings 144, which bearings are mounted in an inwardly projecting portion 146 of the housing 30 (Fig. 8).

30 As is clearly shown in Figs. 6 and 8, the periphery of the disk 140 is provided with a plurality of radially facing notches or recesses 148 to receive lock washers and the disk adjacent its periphery is substantially cut away to a thickness not substantially more than the thickness

of the washers to be handled. Figure 8 clearly illustrates the manner in which the peripheral portion of the disk 140 rotates in contiguity to the annular bracket 136, so that washers received within the recess 148 will be carried in an annular or curved path by the disk while sliding upon the upper surface of the bracket 136.

From the foregoing it will be evident that washers massed at random within the hopper shell are permitted to fall into the recesses adjacent the lower part of the disk 140. The present invention contemplates the rotation of this disk in a counter-clockwise direction as viewed in Figure 6, to convey the selected washers in the recesses to a point just beneath the lower extremity of the delivery chute 18. In order to assure successive placement of washers within the recesses 148, a plurality of radial baffles or plates 150 project inwardly from the shell wall 134 and are each spaced a short distance above the conveyor disk 140. These plates 150 function to retain the washers of the mass against rotation with the conveyor plate 140 and to re-arrange the washers in position suitable for reception within the recesses 148, it being apparent that to pass between the plate 150 and the disk 140 it is necessary that the washers be aligned in substantial parallelism with the disk (see Fig. 8).

Means is provided to advance the shaft 142 and, accordingly, the conveyor plate 140 rotationally step by step, each increment of advance being equal to the space between the centers of two adjacent recesses 148. To this end a driving motor 152 on the lower wall of the housing 30 (Fig. 4) drives a shaft 156, journaled in the lower wall of the housing, through worm reduction gearing 158. Shaft 156 in turn, through sprocket and chain drive means 160, continuously rotates a shaft 162 journaled in an outwardly projecting integral bracket portion 164 formed on an inner wall of the housing 30 (Figs. 4 and 7). A spaced parallel shaft 166, also journaled in the projecting portion of the bracket 164, as well as an integral annular flange 167 upon the upper wall of the housing 30 (Fig. 8) is driven from shaft 162 by spur gear 168 (Figs. 4 and 7) meshing with a gear 170 on the shaft 166. The shaft 162 mounts a cam 172 for rotation. This cam cooperates with a cam follower 174 mounted on rocker or pawl plate 176. It should be noted that the rocker plate 176 is journaled for rotation relative to the lower end of the shaft 142 in accordance with a construction clearly shown in Figure 8. This construction provides an index or ratchet wheel 178 keyed upon the lower end of rotatable shaft 142 the ratchet wheel being shouldered as at 180 for bearing engagement within an aperture in the plate 176, this latter plate being retained in position by means of a retaining collar 182 and jam nut 184. A pawl 186 is pivoted upon the plate 176 as at 188 for engagement with the teeth of the ratchet wheel 178 and is normally urged into engagement with the ratchet by means of compression spring 190 operating between a recess 192 in the pawl and an abutment 194 on the upper surface of the plate 176. A coil spring 196, extending between an extension of the pivot 188 and an adjustable fastening 198 on the wall of the housing 30, resiliently urges the rotatable plate 176 in a counter-clockwise direction as shown in Fig. 7 to retain the follower 174 against the cam 172.

It will be obvious from the foregoing that as the cam follower 174 moves to the right it tends

to carry with it the pawl 186, for moving the ratchet wheel a distance corresponding to one tooth space. It will be understood that the pawl formation is such as to forcibly urge the ratchet in a counter-clockwise direction, while causing the pawl to slide over the periphery of the ratchet wheel when the plate 176 is moved in the clockwise direction.

An indexing means is provided for positively retaining the rotatable disc at each position of advance and comprises an indexing finger 200, slidably arranged in a bracket 202 and resiliently urged toward the ratchet wheel by compression spring 204 (Fig. 7). Indexing finger 200 is retracted by means of one end of a bell crank lever 206 journaled on pivot 208. The opposite end or arm of the bell crank lever 206 mounts an anti-friction shoe 210 providing a follower cooperating with a cam 212 keyed on shaft 166. After each successive advancement of the ratchet wheel 178 the cam 212 permits the bell crank to move in a counter-clockwise direction for permitting index finger 200 to engage the ratchet wheel. The ratchet wheel, its shaft 142, and the conveyor disk 140 accordingly remain stationary for a predetermined increment of time until the advancing mechanism is again actuated to rotate the plate through the next successive increment of rotational advance. From the foregoing it will be apparent that the step-wise movement of the plate is continuously effected as long as the drive motor 152 is in operation.

Attention is particularly directed to the fact that the step-wise movement of the disk 140 cooperates with the inclined arrangement of the plate to dislodge any washers not completely received within the recesses 148; that is to say, as the peripheral recesses 148 move away from the charge of washers which are massed adjacent the bottom of the hopper or shell construction, any washers which are not fully engaged within the recesses tend to gravitate down the inclined face of the plate 140. The jerking movement caused by the interrupted action of the ratchet drive mechanism cooperates to assist in dislodging excess or improperly positioned washers and to assure their proper positioning within the respective recesses 148.

It may sometimes occur that in spite of this construction the tooth portions of adjacent washers will become interengaged to cause one or more excess washers to be conveyed adjacent a properly received washer. Resilient fingers or baffles 214 (Figs. 6, 20 and 21) positively prevent the delivery to the assembly station of more than one washer in each recess. The action of these baffle members is clearly illustrated in Fig. 20, where it will be seen that they comprise a downwardly extending more or less resilient flange 216 secured to the shell 134 as at 218. It should be noted that the lower edge of the wall or flange 216 provides a recess 220 bounded at its inner extremity by means of a downwardly projecting lug 222. As clearly shown in Fig. 20, the recess 220 is of sufficient depth to accommodate the passage of one excess washer. It is of great importance to note, however, that the width of the recess 220, as defined by the wall 134 and the lug 222 is less than the diameter of the lower washer received within the recess 148 in the delivery disk 140 and designated for purposes of illustration by the letter A. In other words, the recess 220 is radially shortened and possesses a radial dimension less than that of a washer. As a result of this arrangement any

excess washer improperly superimposed upon a washer A will necessarily register with the recess 220 so that its peripheral prong portions engage with the lug or projection 222. By virtue of the fact that the lug 222 is fixed and immovable upon the hopper shell 134, further movement of the conveyor disk will cause the excess washer to rotate or shift it about the relatively fixed point of engagement with the lug 222, causing positive dislodgment.

The individual washers received within the recesses 148 progressively move to an assembly station adjacent the lower end of the screw blank delivery chute 18 and just over the lower bars 68 and 70 of the assembly chute 64, as shown in Figs. 4, 6, 8, and 18. Accordingly, it will be understood that the annular continuity of the shell 134 and bracket construction 136 is relieved at this point to permit the peripheral edge of the delivery disk 140 to project over the delivery chute or track 64. So, also, it will be apparent that at this point the annular continuity of the shell 134, which functions to retain washers radially within the outwardly facing recesses, is interrupted to permit radial retraction of the assembly. Thus the fastener element at this point is shifted into the central aperture of each respective washer and further progressive movement of the plate 140 causes each assembled washer and screw to be extracted from its recess 148 by the engagement of the screw shank with the delivery track 64.

The assembly mechanism

The assembly mechanism for receiving the screw elements one by one from the delivery chute 18 and projecting them through the aperture in the successive lock washers is shown in detail in Figs. 4, 6, 8 to 14, and 17. As each screw element is delivered to the end of the chute 18, it gravitates into a recess 224 (Fig. 14) formed in a pair of engaging jaws 226. The jaws move downwardly to project the lower end of the screw element through the aperture in a lock washer. Upon further movement, the jaws 226 are oppositely retracted beyond the head of the fastener and a central shifting bar 230 moves downwardly against the head of the fastener, finally and positively associating it with the washer (Fig. 12).

The jaws 226 are pivotally mounted as at 232 upon a vertically reciprocable slide 234 journaled in a housing 236 (Figs. 4, 8, 12, and 13). The slide 234 has a generally cylindrical body portion embraced by an anti-friction bearing lining 238 in the fixed housing 236, so that the slide is freely shiftable longitudinally in a direction axially of the cylinder. To steady the relatively movable parts, a friction brake block 240 extends through the side wall of the housing 236 and bearing liner 238 into contact with the shiftable member 234 and is urged into engagement by leaf spring means 242, fulcrumed by pin 244 and tensioned by intermediate machine screw 246 engaging the housing 236. The fixed housing 236 is mounted upon a projecting bracket portion or arm 237 (Figs. 4 and 8) of an upwardly projecting pedestal 239 rigidly mounted on the upper surface of the housing 30. For purposes of convenience, the housing 236 is engaged slidably with the end of bracket arm 237 by means providing lateral adjustment to and from the plane of interengagement 241, this construction facilitating alignment of the assembly mechanism with the delivery channels.

The pivoted jaws 226 have the form of bell cranks (Fig. 14) having laterally projecting arms 248 engaged by projections 250 on a laterally extending, resiliently mounted bar 252 urged downwardly and away from the main portion of the slide 234 by a pair of compression springs 254. The resilient force applied upon the projecting arms 248 therefore retains the lower portion of the jaws 226 in closed position, as clearly shown in Fig. 13. Opening or spreading of the jaws just before final driving of the screw element into assembled position is effected by abutment means comprising a pair of adjustable stop screws 256, threadedly supported in the lower portions of brackets 258 integral with the fixed housing 236. As shown in Figs. 12 and 13, the adjustable abutment members 256 reside just below the extremities of the laterally extending jaw arms 248 in position to contact and rotationally shift the jaw mechanism when the slide has reached its lower position. This action of the parts is specifically illustrated in Figure 12 wherein it will be noted that the impingement of the ends of the arms 248 upon the fixed abutment screws 256 has caused the arms 248 to move upwardly against the resilient action of the springs 254, whereby the jaws are spread or shifted outwardly to clear the head of the screw blank.

During this action, the shifting or driving bar 230 comes into action. This bar 230 is rigid with a sleeve 259, movable axially within a central bore in the slide 234. It should be noted that the sleeve has a flange 260 at its lower extremity, limiting the upward movement of the sleeve 259 with respect to the slide. Jam nuts 261 on the upper threaded portion of the sleeve 259 similarly limit downward movement of the slide and may be adjustably positioned in order to predetermine the relative movement between the parts. It should be noted that the rigid interconnection between the driving bar 230 and the sleeve 259 is adjustably maintained by means of interfitting threads and the lock nut 262 at the upper extremity of the parts, whereby the bar 230 may be adjusted into proper driving relationship with fastener heads of varying size and shape. Since, as will hereinafter more fully appear, the entire slide assembly is driven by means engaging the sleeve 259, it will be evident that the slide 234 normally rests and is supported upon the lower flange 260 of the sleeve 259, as clearly shown in Figure 13. When the slide has been permitted to fall to its lower position, however, the bar 230 may move axially into fastener driving position, as clearly shown in Figure 12.

From the foregoing, it will be manifest that shifting of the vertically reciprocable slide 234 and its associated parts between predetermined elevations will cause screw elements to be successively engaged by the jaws 226, conveyed downwardly into association with a washer and then released by said jaws and positively driven into engagement with the washer.

The mechanism for accomplishing the shifting of the foregoing slide construction comprises a bracket arm 264 rigidly engaged with the sleeve 258 by jam nuts 266. The opposite extremity of the bracket arm 264 (Figs. 4, 6, and 8) is rigid with the vertically shiftable control bar 268, slidable longitudinally within the upstanding pedestal 239 which is bored centrally for this purpose and provided with a bearing liner 270. A compression coil spring 272, embracing the shaft or bar 268 within the sleeve or pedestal 239 (see Fig. 8), abuts oppositely against a collar

274 on shaft 268 and against the sleeve liner 270 to urge the shaft and the remainder of the shiftable assembly mechanism toward its lowermost position. Movement upwardly against the tension of the spring 272 is effected by means of a cam member 276 rigid with shaft 166 and engaged by cam follower 277 on the lower extremity of shaft 268. It will be understood that shaft 166 is the shaft hitherto described in detail and which is constantly driven to actuate the indexing mechanism for effecting control of the washer conveying disk.

It will be obvious, therefore, that this shaft additionally functions to actuate the cam mechanism which results in the individual shifting of the screw elements into assembled association with the respective washers. More specifically, upon actuation, the continuously rotating cam 276 alternately raises and lowers the follower 277 and accordingly the shaft 268 and the arm 264 to cause the slide 234 and associated jaw construction to move from an upper position wherein a screw blank is received from the chute 78 to a lower position wherein the screw blank is driven into position and then released.

Downward movement of the rod 230 is limited by the engagement of the head of an adjustable set screw 278 (Fig. 8) carried by the arm 264 with the stationary arm 237, the set screw being slidably guided at its unthreaded end in an aperture in the arm 237. A yieldable washer 279 absorbs the force of the engagement between the screw and arm 237.

Means for controlling operation of the fastener shifting and assembling mechanism in accordance with the delivery of a washer to assembly position

The control of the screw blank assembly mechanism for preventing the delivery of incomplete assemblies to the delivery track 64 is illustrated more in detail in Figs. 4, 6, 8 to 13, incl., 17, 18, and 19. In accordance with this construction as stated above the detector mechanism 26, arranged adjacent the assembly point, closes an electrical circuit when any of the recesses 148 arrives at the assembly point in empty condition, the circuit serving to maintain the reciprocating portions of the screw blank shifting and driving mechanism positively in upper inoperative position until such time as a properly positioned washer arrives at the assembly point.

The detector mechanism comprises a housing 280 rigidly secured to the upper surface of the housing 30 by means 282 permitting lateral adjustment of the device to accommodate the assembly of washers of varying size, as will hereinafter more fully appear. Control lever 284, pivoted on the housing as at 286, extends outwardly thereof and supports upon its extremity a rotatable follower or roller 288. It should be noted that the bar 70 of the assembly delivery track or chute 64 is relieved or recessed as at 290 so that the periphery of the roller may extend into the recesses 148. As clearly shown in Figs. 12 and 13, the outer periphery of the roller 288 is arranged in the same plane with the recesses 148. A spring arm 292 urges the roller 288 into the said recesses, this movement being adjustably limited by means of an adjustment screw 294. A switch 295, operated by adjustable set screw 296 on lever 284, completes an electrical circuit when the lever arm 284 is rotated to its limiting clockwise position, as, for example, when the adjacent recess 148 has arrived at the assembly

point devoid of a lock washer as shown in Fig. 19. At other times, however, the roller rides against the periphery of the conveyor disk 140 or in contact with the peripheral portions of washers contained within the recesses 148, as clearly shown in Fig. 18, to break the foregoing electrical circuit.

The aforesaid electrical circuit effects control of a solenoid 298 mounted upon a bracket 300 at the upper portion of the pedestal support 239 (see Figs. 6, 8, and 9). The armature of the solenoid is rigid with the laterally extending block 302 resting upon the upper surface of the pedestal 239. As clearly shown in Figs. 10 and 11, the block 302 is configurated with an interlocking tooth portion along its upper edge as at 304 for engagement with a notched recess 306 in the vertically shiftable control shaft 268.

The block is normally held disengaged from the reciprocating shaft 268 when the solenoid is de-energized by means of a tension coil spring 308, engaging the end of the armature and a laterally extending portion 310 of the bracket 300 (see Figs. 6 and 9). Outward movement of the control block 302 is limited by means of an adjustable abutment screw 312 carried by the portion 310 of the bracket 300.

From the foregoing it will be readily understood that as long as the recesses 148 in the conveyor dial are occupied, the solenoid 298 will remain unenergized. Should an unoccupied recess 148 reach the assembly point, detector roller 288 is permitted to move into the recess to close the circuit to the solenoid at the points 295, thus actuating the armature to draw the control block 302 against the shiftable bar 268. As the bar starts to descend control the assembly operation, the block 302 engages into the recess 306 to lock the entire shiftable assembly in its uppermost position. Locking engagement is retained until the conveyor plate again moves to move the lever 284 and effect de-energization of the solenoid, after which a subsequent slight elevating action of the cam 276 permits the block 302 to be retracted, whereupon the assembly operation continues as before.

The operation of the machine as a whole

From the foregoing it will be apparent that the body of screw blanks, either threaded or unthreaded, dumped or massed within the hopper 74, are continuously, through the feed action of reciprocating plate 106, arranged in the chute 78 and permitted to gravitate downwardly to the foot thereof. The chute 78 is aligned in substantial tangency to the peripheral portions of the rotating conveyor disk which picks up individual washers from a mass or body of washers arranged at random in the washer hopper or shell 134 and conveys the washers one by one to the assembly point below but slightly in advance of the lower end of the chute 78. At this time the washers and the screw elements are respectively supported so that their respective axes are substantially parallel. In accordance with the foregoing, the washer conveyor disk 140 moves with a rotary interrupted or stepwise motion and at the end of each increment of advancement a washer recess 148 containing a washer is brought to rest directly at the assembly point, that is, in direct axial alignment with the recess 224 formed by the screw blank receiving jaws 226. At this time the jaws are in their uppermost position in alignment with the end of the chute 78, wherefore the lowermost screw element gravitates into the

recess as shown in Figs. 13 and 17. The jaws then move downwardly to shift the screw element longitudinally and directly through the central aperture of the washer. As stated in the foregoing remarks, as the jaws 226 approach the washer, they are separated to release the washer head and an axial application of force is made to the head by means of the driving bar 230. At this time it will be noted that the washer of the assembly, while being contained within a recess 148 of the conveyor disk, is nevertheless resting directly upon the top surface of the delivery chute bars 68 and 70 so that a positive application of force to the fastener head may be employed to positively associate the elements in final assembled position. When the assembly is complete, the conveyor disk 140 is again set in motion to convey not only the embraced washer but the assembled screw element away from the point of assembly, as shown clearly in Figs. 18 and 19. It will be noted, however, that since the shank of the screw is embraced at both sides by the longitudinally extending bars 68 and 70 and since these bars extend tangentially to the path of conveyance, the assemblies are gradually extracted or ejected from their recesses and thus delivered directly to the inclined chute 64 along which they gravitate to the transfer mechanism of the thread rolling machine.

Assuming that the operator should fail to supply washers to the washer receiving hopper or shell, the conveyor disk would continue to move rotationally in stepwise order to, one by one, align the peripheral recesses with the slot in the lower guide 64. Upon movement of an unoccupied recess to the point of assembly, the detector roller 288 moves into the unoccupied recess to cause the control circuit of the solenoid 298 to be closed and the solenoid instantaneously moves the stop block 302 into engagement with the reciprocating rod of the assembly mechanism to retain it in inoperative position. When an occupied recess 148 reaches the point of assembly, the roller is moved backwardly, the circuit opened, and the solenoid de-energized to release the reciprocating rod and permit direction of a screw element into the washer. It will be apparent from the foregoing that the present machine is automatic in operation and positively assures the supply of only properly assembled units to the thread rolling device. The present invention, moreover, provides for the depositing of individual washers from a random mass into a conveyor in predetermined supported position with respect to the conveyor and for the positive conveyance of these washers to a point of assembly. While positively supported, a screw element is inserted within the fastener at a point intermediate of the path of conveyance. The conveyor then proceeds to move to the point of discharge, carrying the assembled unit, and at said point of discharge ejection of the assembly from the conveyor is effected.

After assembly, the screw and washer units gravitate along the chute 64 and in the illustrative embodiment are then transferred to the thread rolling dies 36 and 38 in which a retaining thread is formed on each screw blank beneath its associated washer.

It will be evident that the present invention provides a construction in which a suitable driving force is applied to the head of the fastener to force it into association with the washer, the washer being meanwhile rigidly supported and positively positioned against axial and lateral dis-

placement. The assembly mechanism, accordingly, takes the form of a machine attachment including a press engaging both screw elements and washers to effect assembly thereof, the attachment being fitted on the machine without any substantial modification or rearrangement of the several parts of the machine. Although the present invention has been described in relation to a thread forming machine, it will be evident that in its broader aspects it is not so limited but may be employed in association with any machine or mechanism to which assembled screw and washer units may advantageously be supplied.

From the foregoing it will further be apparent that in accordance with the present disclosure the terms "fastener element" or "screw element" are intended to cover not only the original unthreaded screw blank but also fastener elements in their final threaded condition.

Changes may be made in the form, construction, and arrangement of the several parts without departing from the spirit of the invention or sacrificing any of its numerous advantages, and the right is hereby reserved to make all such changes as fairly fall within the scope of the following claims.

The invention is hereby claimed as follows:

1. In a machine for assembling screw elements and washers, means for conveying screws to a delivery point, means for conveying washers to an assembly point, assembly mechanism including means movable from an inactive position receiving a screw element at this delivery point to carry and insert the screw element into a washer at the assembly point, means adapted to retain the assembly mechanism in inactive position, washer detector means at the assembly point, and means controlled by said detector means for actuating and releasing said retaining means in response to the presence or absence of a washer at the assembly point.

2. In a mechanism for assembling screw and washer elements, a holder for one of said elements and a slide carrying relatively movable members clamping the other of the elements to the slide for movement therewith, means for moving the members relatively to clamp said other element to the slide, means for moving the slide rectilinearly toward the holder to carry said element and telescope it with the complementary element in its holder, and positioned to engage said members as the slide approaches the holder means for then relatively moving the members to release the assembled elements.

3. In a mechanism for assembling screw and washer elements, a washer feed plate having spaced means receiving washers for conveyance by the plate, a slide, relatively shiftable members on said slide for holding a screw element and for carrying and inserting the screw element into a washer, indexing means for actuating said feed plate step by step successively to position the washers in the path of a screw element held by said members, energy storing means for actuating said slide member in a direction to carry and insert the screw element into a washer in the path of the screw element, power actuated means for moving said slide member in the opposite direction and for storing energy in said energy storing means, means for locking said slide member against actuation by said energy storing means, and means operated by the positioning of a washer in the path of a screw element carried in the holding members for releasing said locking means.

4. In a mechanism for assembling screw and washer elements, a stationary guide, a tubular slide mounted in said guide, a pair of oppositely shiftable jaw members movably mounted on said slide, means for urging said jaw members toward closed position to hold a screw element therebetween, means for successively feeding washers to a position in the path of movement of a screw element held in said jaw members, actuating means including a rod slidably mounted within and movable relative to said tubular slide to engage the head of a screw element held in said jaw members and to force the screw element through the washer aperture, electrically operable means for locking said actuating means against movement to actuate said tubular slide, a switch controlling said electrically operable locking means, and a washer sensing device controlling said switch to render said locking means ineffective if a washer is positioned for assembly with a screw element and to render said locking means effective if no washer is positioned for assembly with the screw element.

5. In a mechanism for assembling screw and washer elements, a support, a tubular slide mounted on said support, a pair of oppositely shiftable jaws, means pivotally mounting said jaws on said tubular slide, spring means for urging said jaws toward each other to hold a screw element therebetween, means for feeding washers in succession to a position in the path of movement of a screw element carried by said jaws, means for actuating said tubular slide to carry and telescope a screw element held in said jaws into a washer, each of said jaws having an abutment surface, and an adjustable stationary abutment means on said support and one for each jaw and each adapted to engage an abutment surface of a jaw to move the jaws away from each other to release the screw element after being partially telescoped into the washer and a ram rod within said tubular slide operable relative to the slide for thereafter forcibly pressing the screw element into final telescoped relation with the washer with the clamping head of the screw element adjacent the washer.

6. In a machine for assembling screw elements and washers, means for conveying washers to an assembly point, means for assembling screw elements with the washers at said point, means for actuating the assembly means, means including a washer actuated detector element positioned to engage a washer at the assembly point, and a locking device operatively connected to said detector element for locking said assembly means against actuation by said actuating means when the washer conveyor means fails to deliver a washer to said assembly point.

7. In a machine for assembling screw elements and washers, means for holding a washer at an assembly location, a support, a slide mounted on said support for movement toward and from the washer held by said means at said location, a pair of oppositely shiftable jaws, for receiving a screw element therebetween, means for mounting said jaws on said slide to cause the jaws to carry and partially insert a received screw element through a washer held by said holding means at said location, an actuating slide rod constructed and arranged in relation to the slide and jaws for movement relative to the slide toward and from said washer location to engage a screw element in the jaws and to drive said slide, as well as the jaws holding said screw, toward the washer held by said holding means at said

location to insert said screw element in said washer so located, abutment means carried by said jaws, and stationary abutment means on said support in position to engage said jaw-carried abutment means to release said jaws from the screw therebetween as said screw is inserted in said washer, said stationary abutment means, and said jaw-carried abutment means and said jaw-mounting means being constructed to cause an opening movement of the jaws releasing the screw therebetween prior to the termination of movement of the actuating slide rod, said actuating slide rod, as it continues to move after the jaws are open, pressing the released screw element engaged by said rod into final telescoped relation with said washer held by said washer holding means at said location.

8. In a machine for assembling screw elements and washers, means for holding a washer at an assembly location, a support, a slide mounted on said support for movement toward and from the washer held by said means at said location, a pair of opposing shiftable jaws for receiving a screw element therebetween, means for mounting said jaws on said slide to cause the jaws to carry and partially insert a receiver screw element into a washer held by said holding means at said location, an actuating rod slidably mounted on said support for reciprocating movement toward and from the washer held by the washer holding means at the assembly location, power means for moving said rod, means movable with said slide rod and forming spaced members constructed to engage said slide, following an initial movement of said rod, for causing said slide to move thereafter with said rod and carry said jaws toward the washer held at said location to insert the screw, received between said jaws, in the washer held at said location, and away from said location to position said jaws for the reception of another screw to be assembled, jaw-releasing abutment means carried by said jaws, stationary abutment means on said support and positioned to be engaged by said jaw-carried abutment means for moving said jaws to release the screw as said screw is inserted in said washer, means associated with said slide and said jaws normally urging said jaws toward each other to hold the received screw therebetween, said urging means being constructed and arranged to allow opening movement of said jaws upon engagement of said stationary abutment means with said jaw-carried abutment means, said abutment means being so related that said engagement takes place after partial telescoping of said screw with the washer held by its holding means at said location, said power means being constructed to thereafter continue movement of said rod and slide toward the washer so that said rod will engage and press said released and partially telescoped screw further into said washer and into final telescoped relation therewith.

9. In a machine as set forth in claim 7, wherein there is provided a friction material carried by said support and positioned to engage said slide to hold said slide against movement except by said actuated rod when pressing upon a screw received between said jaws.

10. In a machine as set forth in claim 8, wherein there is provided friction material carried by said support and positioned to engage said slide for holding said slide against movement except by said actuating rod when one of said spaced members engages said slide.

11. In a machine as set forth in claim 7,

wherein the jaw-carried abutment means comprises an abutment surface on each jaw and said stationary abutment means comprises individually adjustable abutments, one for each jaw and each adapted to engage an abutment surface of a jaw to move the jaws away from each other.

12. In a machine as set forth in claim 8, wherein said slide comprises a tube; said support is provided with a tubular sleeve portion slidably receiving said tube; said actuating rod is slidably mounted in said tube and wherein the means movable with said slide and forming spaced members for engaging the slide following an initial movement of the actuating rod includes means adjustably mounting one of said members relative to the slide for adjustment to vary the extent of initial movement of the actuating rod relative to the slide.

13. In a mechanism for assembling screw elements and washers, means for feeding washers successively to an assembly location, a stationary support having a vertical guide above the washer when positioned at said location, a slide mounted in said guide for up and down movement toward and from the washer when so located, a pair of oppositely shiftable jaws for receiving the screw element therebetween, means for pivotally mounting said jaws on said slide for movement with the slide to carry and insert the screw element received between the jaws into a washer at said location when said slide is moved downward toward the washer at said location, an actuating plunger on said slide and projecting

between said jaws for engaging with a screw element when received between said jaws, a driving shaft, driving connections between said shaft and said actuating plunger for reciprocating the plunger up and down upon operation of the driving shaft, means mounting said plunger with respect to the slide for an initial movement relative to the slide to engage a screw received in said jaws upon downward movement of the plunger, said plunger being constructed and arranged to apply through the engaged screw received between said jaws, a downward force upon said jaws causing through the jaws and the means mounting the jaws on the slide a downward movement of the slide with the plunger after the plunger has engaged the screw received between said jaws, means associated with said plunger and said slide for causing the upward movement of the slide with the plunger, said jaws having an abutment surface, and stationary abutment means adjustably mounted on said support and positioned to engage said abutment surfaces for moving the jaws away from each other to release the screw element after being partially telescoped into the washer positioned by the washer feeding means at said location, said driving connections being constructed to continue the movement of said plunger after the screw has been released from said jaws to press the screw into final telescoping relation with the washer.
